UNITED STATES PATENT OFFICE.

JOHN W. MITCHELL, OF BAYONNE, NEW JERSEY.

APPARATUS FOR GENERATING ILLUMINATING AND HEATING GAS.

SPECIFICATION forming part of Letters Patent No. 317,407, dated May 5, 1885.

Application filed March 23, 1885. (No model.)

To all whom it may concern:

Be it known that I, JOHN W. MITCHELL, a citizen of the United States, residing at Bayonne, in the county of Hudson and State of New Jersey, have invented certain new and useful Improvements in Apparatus for Generating Illuminating and Heating Gas; and I do hereby declare the following to be a full, clear, and exact description of the invention, such as will enable others skilled in the art to which it appertains to make and use the same.

This invention relates to improvements in apparatus for the manufacture of gas for heating and illuminating purposes from carbonic-oxide and hydrocarbon gases, each separately generated. The carbonic oxide is cooled before mixing to about the temperature of the hydrocarbon gas discharged from the retorts, at which temperature they are amalgamated or fixed, as more fully hereinafter specified. These effects I attain by the means illustrated in the accompanying drawings, in which—

Figure 1 represents a front elevation of benches of retorts for the generation of the hydrocarbon gas, showing the steam super-heating coils in dotted lines, and below this a cupola-furnace in vertical section, as well as a blast apparatus in elevation, whereby the carbonic-oxide gas is generated. Fig. 2 represents a rear elevation of the benches of retorts with a portion of the brick-work broken away, exposing the retort-connections and superheating-pipes. Fig. 3 is a vertical section on line x x , Fig. 1, showing one retort in section and the others in elevation. Fig. 4 represents a sectional view of the mixing-chamber or amalgamator and the tank through which the carbonic-oxide-gas conduit passes; Fig. 5, a sectional view of the injector, whereby the oil is sprayed into the retorts by means of a jet of steam.

The letter A indicates a furnace, constructed of brick-work or any other suitable material, and is divided into three compartments, a b c , by means of vertical partition-walls. The side compartments of the furnace have located in them the retorts C D E, which are arranged in benches, as shown in Figs. 1, 2, and 3. The upper retort, E, is made of a capacity about equal to the combined capacity of all the retorts below it, and is for the purpose of completing and perfecting the decomposition of

the products which pass through it from the retorts below. This is to insure the conversion of any undecomposed vapor that may have passed from the retorts below and prevent it from being carried forward with the fixed gas to the mixing-chamber. The intermediate chamber is provided with a series of heating coils or pipes, F, for the purpose of superheating steam. The furnace is located on the first floor of a retort-house or other structure, and supported upon trussed girders or arches, G, or in any other suitable manner, and below said furnace is located a cupola, H, of the usual or any approved construction, which is provided with grate-bars I. A space for the ash-pit is provided, to which access may be had through gas-tight doors. A blower, K, connects with the cupola just below the grate-bars, for forcing a current of air through the furnace and the burning fuel with which it is charged. The cupola communicates with the side chambers, a and c , of the furnace by means of the oblique flues L, so as to discharge the hot gases generated by the combustion of the fuel into said chambers, as will be seen by reference to Fig. 1 of the drawings. The said chambers a and c , as well as the central chamber, b , are arched at their tops, as shown in dotted lines in Fig. 1, so as to cause a deflection downward of the heated gases after reaching the tops of the chambers. The partition-walls e between the chambers a b c are formed with short transverse flues g at the front and rear, leading from the lower portions of said chambers a and c into the chamber b , and the said walls are also provided with central vertical escape-flues, h, leading upward from the lower part of the chamber b into the interior of the dome or compartment N above the chambers of the furnace. These vertical flues lead in from the chamber at a point below the transverse openings g.

Within the chamber b , running back and forth, is a series of coils of pipes, E, which connect at one end with a steam-boiler through a pipe, i, and through the pipes m n with the branch pipes p , leading to the interior tubes of the injector r , projecting into the lower and middle series of the retorts in the respective benches, as indicated in Figs. 1 and 2 of the drawings. The inner tubes of the injectors

are continuations of the oil-pipes *S*, connecting with the cross-pipes *t*, which in turn couple with a pipe leading from the oil tank *Q*. A pipe, *t'*, having a controlling-valve, *r*, for regulating the automatic flow of oil to the injectors, extends from the oil tank to supply-pipes *s*. The said tank is provided with an agitator, which may be operated by any suitable power, to prevent the heavier portions of the oil from collecting at the bottom of the tank and the pipes, and thereby clogging the passage or flow of the oil. Pipes *u* from the upper retorts connect with a horizontal pipe, *w*, for conducting the hydrocarbon gas to the amalgamator or fixing-chamber. (Shown in Fig. 4 of the drawings.) The rear ends of the retorts of the respective benches are connected by the pipes *Y* and the cross or branch pipes *Z*. From the dome of the furnace a pipe, *y*, extends through a tank, *R*, and then to and connects with the hydrocarbon-gas pipe *w* above the amalgamating-chamber. A branch from the intersection of these pipes extends downward through the top of the amalgamator, wherein the gases are finally commingled at a suitable temperature for amalgamation or proper union. The amalgamator or fixing-chamber consists of a structure of brick-work or any other suitable material. The pipe projecting into the amalgamator is perforated at intervals, to provide for the lateral passage of some of the inflowing gases into the chamber. The main volume of the gases, however, escapes into the chamber through the lower end of the pipe, which is left entirely open and unobstructed for the purpose. At intervals in the interior of the said amalgamator or fixing-chamber are arranged wire-gauze or foraminous diaphragms, which finely divide the gases in passing upward and cause them to come into contact with each other, thus insuring their perfect union and thorough amalgamation or fixing. From the top of the chamber at one side extends a pipe, *J*, through which the fixed gases pass to the washer, from which they are carried by suitable pipes directly to the purifiers and thence to the holder.

In practice, for the sake of convenience, I prefer to have two cupolas for the generation of the carbonic-oxide gas, so arranged and located below the retort-furnace and its benches that one furnace can be in operation while the other is idle, to avoid interruption when cleaning and recharging are necessary, thus providing for a continuous supply of carbonic-oxide gas.

The operation of my invention will be readily understood in connection with the above description, and is as follows: The cupola below the retort-furnace being properly charged with carbonaceous material, and the material ignited, the chamber below the grate-bars is closed air-tight, and a forced current of air of suitable volume and under proper pressure is passed up through the fuel. Combustion is thus carried on, and the hot carbonic-oxide and other gases of combustion are carried up through the

flues into the chambers *a* and *c* and around the retorts therein. The hot gases are then deflected downward, and pass through the short front and rear horizontal flues in the partition-walls into the chamber *b* and around the heating-coils therein. On the way through the chambers *a-c* the hot carbonic-oxide gas parts with a portion of its heat to the retorts, and in its passage through the chamber *b* parts with more of its heat to the heating coils in said chamber, and escapes through the vertical flues *h* in the partition-walls, thence into the dome, and finally off through the submerged coil of pipes to meet the hydrocarbon gas on its way to the amalgamator or fixing-chambers. While this is taking place the oil is being supplied to the injectors through the oil-pipes from the tank, and superheated steam is also being fed to the injectors from the coils. The steam from the boiler is superheated and is injected into the retorts with the oil, where the two are decomposed by the heat imparted to the retorts by the hot carbonic-oxide gas, and the resultant hydrocarbon gases are carried off through the pipes to meet the carbonic-oxide gas on its way to the amalgamator or mixing-chamber, where they enter simultaneously at a proper mean temperature, at which they are united and amalgamated, and finally fixed in said chamber, after which they pass off to the washer, condenser, and purifier, thence to the holder.

It is observed that the operations of this apparatus are substantially automatic.

Having thus described my invention, what I claim, and desire to secure by Letters Patent, is—

1. A furnace for generating carbonic-oxide gas, a retort or bench of retorts, means for supplying hydrocarbon and steam to said retorts for generating hydrocarbon gas, and coils for superheating steam, combined and arranged for operation substantially as specified, whereby carbonic-oxide gas is generated, and by its surplus heat the contents of the retorts are decomposed and the steam is superheated.

2. The combination of a cupola-furnace for generating carbonic-oxide gas, a retort-furnace, a flue or flues leading from the former to the latter, a retort or bench of retorts, means for supplying hydrocarbon and steam to said retorts, and a conduit leading from the cupola-furnace through a water-tank to join a separate conduit leading from the retorts at the amalgamator, substantially as described.

3. The combination, with the cupola-furnace and the retort-furnace and retorts, of the steam-coils extending through a chamber, *b*, located between the retort-chambers, which communicate with said intermediate chamber; and the injectors connecting with said coils and with the oil-supply pipes, whereby the steam may be heated by the surplus heat of the carbonic-oxide gas and the gas further cooled previous to passing to the amalgamator, substantially as and for the purpose specified.

4. The combination, with the retort-furnace

having two retort-chambers and an intermediate heating-chamber, of the dividing-partitions, the flues by which the chambers are connected, and the vertical flues leading to the dome, from whence the carbonic-oxide gas is conveyed to the amalgamator, substantially as specified.

5. The combination of the cupola-furnace, the chambered retort-furnace, the retorts and the steam-heating coils, the injectors, the oil-supply pipes, the regulating-valve, and the oil-tank, substantially as and for the purpose set forth.

10. The combination, with the cupola-furnace and the retorts, of the retort-connecting pipes at the rear, the injectors, oil and steam supply

15. pipes, and separate pipes for the gases connecting with the amalgamator or fixing-chamber, substantially as and for the purpose specified.

7. The combination, with the amalgamator or fixing-chamber, of the inlet-pipe at one end and discharge pipe at the other, and wire-gauze or foraminous diaphragms, substantially as described.

In testimony whereof I affix my signature in presence of two witnesses.

JNO. W. MITCHELL.
